(57) **CLAIM**

The ornamental design for an accessibility ruler, as shown and described.

DESCRIPTION

FIG. 1 is a top plan view of my accessibility ruler showing my new design when folded;

FIG. 2 is a left side view of the design of FIG. 1;

FIG. 3 is a right side view of the design of FIG. 1;

FIG. 4 is a bottom plan view of the design of FIG. 1;

FIG. 5 is a front end view of the design of FIG. 1;

FIG. 6 is a rear end view of the design of FIG. 1;

FIG. 7 is a top plan view of my accessibility ruler showing my new design when extended;

FIG. 8 is a left side view of the design of FIG. 7;

FIG. 9 is a right side view of the design of FIG. 7;

FIG. 10 is a bottom plan view of the design of FIG. 7;

FIG. 11 is a front end view of the design of FIG. 7;

FIG. 12 is a rear end view of the design of FIG. 7;

FIG. 13 is an enlarged top plan view of a portion of the design of FIG. 1;

FIG. 14 is an enlarged top plan view of a second portion of the design of FIG. 1; and,

FIG. 15 is an enlarged top plan view of a third portion of the design of FIG. 1.
